UNITED STATES PATENT OFFICE

157,599

KETTLE

Betty Hatcher John, Dayton, Ohio, and James L. Hvale, Chicago, Ill., assignors to Ekeo Products Company, Chicago, Ill., a corporation of Illinois

Application February 7, 1948, Serial No. 144,348

Term of patent 7 years

(Cl. D44—25)

To all whom it may concern:

Be it known that we, Betty Hatcher John and James L. Hvale, both citizens of the United States, residing at Dayton, county of Montgomery, State of Ohio, and Chicago, county of Cook, State of Illinois, respectively, have invented a new, original, and ornamental Design for a Kettle, of which the following is a specification, reference being had to the accompanying drawing, forming part thereof.

Fig. 1 is a perspective view of a kettle, showing our new design; and

Fig. 2 is a top plan view thereof.

We claim:

The ornamental design for a kettle, as shown.

BETTY HATCHER JOHN.

JAMES L. HVALE.
